CIGARETTE SAVER

Richard E. Cook, Trenton, N. J.

Application November 16, 1936, Serial No. 111,128

4 Claims. (Cl. 206—41)

This invention relates to cigarette savers and has for an object to provide a novel device for saving, for future use, a partly smoked cigarette.

Often, rather than discard a partly smoked cigarette a smoker will remove the burning end with the fingers or against the side of an ash tray. Removing the burning end in this manner leaves the finger tips soiled, smelling of burned tobacco, and also leaves the end of the cigarette 10 blackened and charred when relighted. The charred end is bitter to the taste and unpleasant, when the user resumes smoking.

With the above disadvantages in mind the present invention provides a cylinder for receiving and retaining the cigarette, the cylinder having a novel knife attached thereto for cutting off the burned or charred end of the cigarette.

With the above and other objects in view the invention consists of certain novel details of construction and combinations of parts herein-after fully described and claimed, it being understood that various modifications may be resorted to within the scope of the appended claims without departing from the spirit or sacrificing any of the advantages of the invention.

In the accompanying drawing forming part of this specification,

Figure 1 is a side elevation of a cigarette saver, constructed in accordance with the invention and having portions broken away.

Figure 2 is a longitudinal sectional view taken on the line 2—2 of Figure 1.

Figure 3 is an end elevation of the rotary cap and showing the cam slot for actuating the knife.

Figure 4 is an end elevation of the cylinder showing the knife.

Referring now to the drawing in which like characters of reference designate similar parts in the various views, 10 designates a cylinder having a cylindrical bore 11 of sufficient diameter to receive a cigarette 12. A cap 13 is provided with ears 14 through which pins 15 are passed 45 into longitudinal slots 16 formed in the sides of the cylinder near one end thereof. The cap forms a closure for the end of the cylinder when the pins 15 are slid to the inner ends of the slots 16. When the pins are slid to the outer ends 50 of the slots 16 the cap may be rocked on the pins as an axis, as shown in Figure 1, to permit insertion and removal of a cigarette.

The end of the cylinder opposite the cap is enlarged as shown at 17 and at the extreme end 55 is uniformly reduced to provide a cylindrical

bearing surface 18 in which are located a plurality of concave notches 19.

A rotary cap 20 forms a closure for the enlarged end of the cylinder. The cap is provided with a cylindrical lip 21 adapted to loosely fit 5 the cylindrical surface 18 of the cylinder. A plurality of ball stops 22 are seated in radial recesses in the lip and are urged toward the axis on the cap by a helical spring 23. These ball stops when seated in the concave notches 19 10 detachably secure the cap to the cylinder. However, the cap may be rotated on the cylindrical surface 18, for the purpose of cutting off the burning end of a cigarette, as will presently be described, and during such rotary movement 15 the ball stops 22 ride into and out of the notches 19 as will be understood.

A knife 24 is mounted on the end face of the enlarged portion of the cylinder 11. The knife is pivotally mounted at one end on the cylinder 20 by means of a pivot screw 25 and is swingable on the screw across the bore 11 of the cylinder to sever the burning end of a cigarette. The free end of the knife is provided with a cam pin 26 which is movable radially in a cam slot 27 25 formed in the end face of the cap 20 to swing the knife through its cutting stroke when the cap 20 is rotated.

A push rod 28 is mounted in an axial opening 29 formed in the cap 20 and is equipped with a 30 disc head 30, formed preferably of insulating material, for ejecting the severed burning end of a cigarette after the cap 20 is removed from the cylinder subsequent to the cutting operation. A helical expansion spring 31 is sleeved on the push 35 rod to return the push rod to neutral position after each actuation.

A pair of oppositely disposed longitudinal slots 32 are formed in the cylinder 10. These slots permit the smoker to insert the tips of the forefinger and thumb against a cigarette to frictionally engage the same and assist in removing the cigarette from the cylinder. However, but one slot may be utilized, or when desired the cigarette may be removed by simply inverting the cylinder 45 so that the cigarette will drop out by gravity.

In operation the hinged cap 13 is swung to a position laterally of the cylinder 10 and the burning cigarette is inserted endwise, with the burning end first, in the cylinder. The burning end of the cigarette will be received in the rotary cap 20. The cap 13 may now be swung back to close the cylinder in rear of the cigarette whereupon the rotary cap 20 may be rotated through an arc of about 180 degrees to cause the cutting edge of 55

the knife 24 to shear off the burned end of the cigarette. The rotary cap 20 may now be pulled off to allow the cut off portion of the cigarette to drop out. The cap 20 may now be replaced 5 to form a closure for the cylinder in front of the cigarette so that the cigarette is housed in the cylinder until such time as the smoker desires to again light the cigarette.

From the above description it is thought that 10 the construction and operation of the invention will be fully understood without further explanation.

What is claimed is:

1. A cigarette saver comprising a cylinder for 15 receiving and retaining a cigarette, a cap detachably and rotatably mounted on one end of the cylinder, and a knife carried by the cylinder and connected to the cap whereby rotation of the cap swings the knife across the bore of the cylinder 20 to cut off the burned or charred end of the cigarette.

2. A cigarette saver comprising a cylinder for 25 receiving and retaining a cigarette, a closure for one end of the cylinder, a closure for the opposite end of the cylinder, means for detachably and rotatably mounting the last named closure on the cylinder, and a knife between the last named

closure and the cylinder and connected to the closure for rotary movement as a unit therewith to cut off the burned or charred end of a cigarette.

3. A cigarette saver comprising a cylinder for 5 receiving and retaining a cigarette, a bearing surface on one end of the cylinder, a cap having an annular lip rotatably engaging the bearing surface, yielding stop means between the lip and the bearing surface removably securing the cap to the cylinder while permitting rotation of the cap on the cylinder, and a knife assembled with the cylinder and connected to the cap to be moved by rotation of the cap across the bore of the cylinder to cut off the burned or charred end of a 10 cigarette.

4. A cigarette saver comprising a cylinder for 15 receiving and retaining a cigarette, a cap rotatably and removably mounted on one end of the cylinder, a radially disposed slot in the cap forming a cam device, a blade pivoted at one end in the cylinder, and a projection on the other end of the blade engaged in said slot and moving the blade across the bore of the cylinder when the cap is rotated on the cylinder to cut off the 20 burned or charred end of a cigarette.
